CONTAINER FOR WRENCHES AND THE LIKE

Elbert H. Carroll, West Boylston, Mass.

Application March 24, 1931, Serial No. 524,917

Renewed December 15, 1933

4 Claims. (Cl. 206—16)

This invention relates to a socket wrench set comprising a plurality of sockets of graduated size, and one or more common handles which are provided for use selectively with any one of said socketed members.

The invention resides in the compact assemblage of such a set in a specially constructed holder or container of simple and inexpensive construction, and adapted to prevent accidental displacement of the parts of the set, although permitting each part to be individually removed with ease when desired.

Further advantages and objects of the invention will appear from the following detailed description taken in connection with the accompanying drawings, in which:—

Fig. 1 is an elevation view of the device of the invention in closed position, with parts broken away to show certain details.

Fig. 2 is a plan view of the device in open position.

Fig. 3 is an end elevation of the device in the closed position of Fig. 1.

Fig. 4 is an end elevation of the device in the open position of Fig. 2.

Fig. 5 is an end elevation of the device in the position of Fig. 1, being the end opposite to the end of Fig. 4.

Fig. 6 is a plan view of the device in closed position, parts being broken away to show the construction.

Like reference characters refer to like parts in the different figures.

A socket wrench set of the type referred to provides, as is well-known, a plurality of similarly shaped socket members 1, 2, 3, 4, 5, 6, 7 and 8, graduated in size, and each having a nut or bolt-receiving socket, here shown as hexagonal in form, and adapted to fit a given size of nut or bolt, ranging from a large nut or bolt, for which the member 1 is provided, to a small nut or bolt, for which the member 8 is provided,—intermediate sizes being taken care of by the socket members 2 and 7 inclusive. These socket members are graduated not only as to diameter but also as to depth, and each provides, in addition to its socketed nut-engaging portion, a polygonal opening 9, all of the openings 9 being of the same size and shape, so as to be capable of operative engagement with the similarly shaped handle or shank member 10, common to all of said socket members.

As here shown, the openings 9 are hexagonal and the handle member 10 is of hexagonal section to fit all of said openings 9. Preferably, as shown in Fig. 6, one end of the shank or handle

10 is bent at right angles, as indicated at 11; either end of the handle can be inserted in any of the socket members, depending upon whether the long portion or the short portion of the handle is to be used as a lever arm. The present wrench set includes, in addition to the usual handle 10, a ratcheting device or handle 12 of ordinary construction, adapted for use selectively with any one of the socket members 1 to 8 inclusive of the set. The member 12 provides a ratchet block 13 having a hexagonal opening 14 therethrough for the entrance of a similarly shaped extension member 15, one end of which, in the manner of the ends of handle 10, is adapted to be operatively engaged with any one of the socket members 1 to 8 inclusive. The extension member 15 provides at its opposite end a screw driver blade 16, so that the set also affords, when desired, a ratcheting screw driver.

According to the present invention a shallow tray or holder 17 is provided for the socket members, said tray being formed preferably from a single elongated piece of sheet metal whose longitudinal edges are bent up at right angles to the central bottom portion to provide side walls 18 and whose ends are bent up to provide parallel end walls 19 of comparatively greater height than the side walls 18. The tray 17 is adapted to receive the socket members 1 to 8 inclusive laid in a row against the bottom thereof; and preferably decreases in width adjacent the smaller sockets to prevent transverse sliding of the socket members. The tray as constructed is somewhat longer than the row of socket members, and the material of the bottom is struck up to provide a transverse tongue 20 of approximately the height of the side walls and engaging the smallest socket member 8 in order to hold the socket members in one end of the tray and against sliding movement.

A cover 21, which receives the handles, is formed preferably from a single piece of sheet metal, the longitudinal edges of which are bent at right angles to the central side wall portion to define parallel top and bottom walls 22 and 23, respectively, the outer edges of the top and bottom walls being bent toward each other at 24 to define retaining flanges parallel to the central side wall portion. The bottom wall 23 of the cover is provided at opposite ends with extending portions which are bent downwardly substantially at right angles thereto to form depending flanges 25. By this construction, the cover 21 forms a compartment for receiving the handles of the socket wrench set, the compartment being open at op-

posite ends to permit independent withdrawal of any of the handles. The handle member 10 extends longitudinally within the cover with the short end thereof resting against the top wall 22, 5 the rebent edge 24 of this wall being cut away at 26 adjacent one end to permit the short portion to project outwardly, as shown in Figs. 1 and 3; said handle is held in position by a plurality of longitudinal upright tongues 27 struck up from the 10 central side wall, each tongue being of a height to engage the long portion of the handle and prevent twisting or sliding thereof within the cover and an additional transverse tongue 28, struck up from the top wall 22, and which engages the 15 remote end of the handle to prevent longitudinal movement inwardly of the cover although permitting withdrawal of the wrench therefrom when desired. The ratchet handle is held against the opposite wall 23 by an upright longitudinal tongue 20 29 struck up from the central side wall and which engages resiliently against the handle substantially midway of the length thereof, and a transverse tongue 30 which is struck up from the bottom wall 23 to engage the inner end of the ratchet member and hold said member resiliently against 25 longitudinal movement in the cover. The extension member 15 is held in the cover adjacent one end by a longitudinal tongue 31 struck up from the central side wall portion of the cover and 30 which holds the extension member resiliently in position; the inner end of the member 15 engages the side of tongue 30 to prevent inward movement of said member. The cover preferably decreases in width adjacent one end corresponding 35 to the decreasing width of the tray.

The cover and tray are pivotally connected together at their opposite ends by suitable pivotal members 32 and 33 with the depending flanges 25 in contact with and between the upstanding ends 40 of the box, the pivotal connections being located adjacent corresponding corners of each of the depending flanges and the lower corners of the tray in order to space the cover slightly above the top surfaces of the socket members as shown in 45 Fig. 1. Cooperating protuberances 34 and 35 are formed respectively on one of the depending flanges and on the corresponding end portion of the tray and are arranged to be brought into engagement when the cover is moved into closed 50 position over the tray, thereby resiliently to hold the tray and cover against opening. The depending flange 25 which connects the cover to the tray at the end adjacent the largest socket member is longer than the opposite depending 55 flange in order that the adjacent wall 23 of the cover may be substantially equally spaced from the top of each socket member.

With the cover and tray in the position shown

60

65

70

75

in Fig. 1, the bottom wall 23 of the cover extends adjacent the upper surfaces of the socket members acting as a closure for the tray and preventing removal of the socket members therefrom, and the end walls of the tray extend upwardly to the top of the cover portion thereby closing the open ends of the compartment in the cover and preventing removal of the handles therein.

To release the parts of the wrench set, the cover is rotated about the pivotal connection to the position shown in Figs. 2 and 4 so that the cover extends adjacent one side of the tray. This permits access to any of the socket members selectively, and, since the ends of the cover are now open, any one of the handles or extension members may be individually withdrawn for use with the desired socket.

I claim,

1. A container for a socket wrench set, comprising a box having an open top and upwardly extending ends, and adapted to receive the graduated sockets of a wrench set, a cover pivotally connected to the ends of said box, said cover having open ends to receive therein the handles of said wrench set, said cover when in closed position preventing access to said box and said upstanding ends on the box closing the open ends of the cover, and means for retaining said box and cover in closed position.

2. A container for a socket wrench set, comprising a box having upwardly projecting ends, a cover having at least one compartment therein, depending flanges at opposite ends of said cover pivotally connected to the ends of said box to permit the cover to be swung for opening or closing the box, the projecting ends of the box closing the compartment in the cover when said cover is in position to close the box.

3. A container for a socket wrench set, comprising a box having upwardly projecting ends, a cover having at least one compartment therein, depending flanges at opposite ends of said cover pivotally connected to the ends of said box so that the cover may be swung for opening or closing the box, the projecting ends of the box closing the compartment in the cover when the cover is in position to close the box, and means for holding the cover in closed position.

4. A container for tools comprising a box having an open top and upwardly extending ends, a cover connected to said ends for movement relative thereto for opening and closing of said box, said cover having a compartment therein open at least at one end thereof, said cover when in closed position preventing access to said box and said upstanding ends on the box closing the opening to the compartment in the cover.

ELBERT H. CARROLL.
